UNITED STATES PATENT OFFICE.

ALMA C. FIELD, OF PROVIDENCE, RHODE ISLAND, ASSIGNOR TO T. E. BENNETT COMPANY, OF PROVIDENCE, RHODE ISLAND, A CORPORATION OF RHODE ISLAND.

DESIGN FOR A LOCKET OR CHARM.

No. 38,320.

Specification for Design.

Patented Nov. 27, 1906.

Application filed October 12, 1906. Serial No. 338,661. Term of patent 3½ years.

To all whom it may concern:

Be it known that I, ALMA C. FIELD, a citizen of the United States, residing at Providence, in the county of Providence and State of Rhode Island, have invented a new, original, and ornamental Design for a Locket, Charm, or the Like, of which the following is a specification, reference being had to the accompanying drawing, forming part thereof.

I claim—

The ornamental design for a locket or charm, as shown.

ALMA C. FIELD.
